UNITED STATES PATENT OFFICE.

CHARLES MORLET, OF LODÈ, SWITZERLAND.

WATCH-BARREL.

SPECIFICATION forming part of Letters Patent No. 629,907, dated August 1, 1899.

Application filed February 16, 1899. Serial No. 705,631. (No model.)

To all whom it may concern:

Be it known that I, CHARLES MORLET, a citizen of the United States of America, residing at Lode, Switzerland, have invented certain new and useful Improvements in Spring-Barrel Mechanism for Watches or Clocks, of which the following is a specification.

This invention consists of an improved spring-barrel mechanism for watches or 10 clocks, and the accompanying drawings show several constructions of such spring-barrel mechanism embodying the invention.

In the drawings, Figure 1 is a cross-section of one construction of the improved spring-barrel mechanism. Fig. 1bis is a top view of 15 Fig. 1. Fig. 2 shows in cross-section and seen from beneath the ring C of the spring-barrel mechanism shown in Fig. 1. Fig. 3 shows in cross-section and seen from beneath the disk 20 or wheel E' of the spring-barrel mechanism shown in Fig. 1. Fig. 4 is a cross-section of a modification of the improved spring-barrel mechanism. Fig. 5 shows in cross-section and seen from beneath the ring C of the same. Fig. 6 shows in cross-section and seen from 25 beneath the disk E² of the construction shown in Fig. 4. Fig. 7 is a cross-section of another modification of the improved spring-barrel mechanism. Fig. 8 shows in cross-section and 30 seen from beneath the ring C of the same. Fig. 9 shows in cross-section and seen from beneath the disk E³ of the construction shown in Fig. 7. Fig. 10 is a cross-section of another form of the improved spring-barrel 35 mechanism. Fig. 11 shows in cross-section and seen from beneath the ring C of the same. Fig. 12 shows in cross-section and elevation from beneath the disk E⁴ of the construction shown in Fig. 10.

40 In the several figures of the drawings the same letters of reference refer to the same parts.

A is the shaft of the spring-barrel mechanism, which is provided with a collar a, made 45 of one piece with the said shaft and provided with a tooth or finger a', Fig. 1bis, which is intended to engage the usual stop-wheel F, pivoted to the mainspring-barrel B, in view of limiting the number of revolutions of the 50 said mainspring-barrel with regard to the shaft A. The said stop-wheel F may be of any suitable construction.

The mainspring-barrel B has an inner hub b, in which the shaft A is free and around

which is rotatively mounted the ring C, Fig. 55 2, the hook c of which receives the inner end of the mainspring D within the said mainspring-barrel B. The outer end of the mainspring D is fixed to the inner wall of the said mainspring-barrel B. The ring C is free on the 60 hub b of the barrel B; but it is provided with a pin or projection c', which engages loosely with the disk E', Fig. 3, which is fixed on a square portion of the axis A. The opening e' is large enough to have the pin or projection c' engaging the same with some play, the purpose of this being to allow the ring C to make a slight backward rotation when the mainspring has been wound up. The ring C 65 around the hub b acts like a brake when the mainspring is wound to top.

The disk E' may be toothed, as shown in Fig. 3, to engage with a winding-wheel of usual construction, or the said disk may be made of the same diameter as the ring C, as 75 shown at E² in Figs. 4 and 6, or at E³, as shown in Figs. 7 and 9. In these two latter cases the said disk E² or E³ is within the mainspring-barrel B, as shown in the Figs. 4 and 7.

In Figs. 4 and 6 the disk E² is provided with 80 an opening or notch e², in which engages the pin c' of the ring C. In Figs. 7 to 9 the ring C is formed with two projections c, engaging two corresponding openings e³ of the disk E³.

In the construction shown in Figs. 10 to 12 85 the disk E⁴ is made of the same diameter as the inner portion of the mainspring-barrel, and it is like a cover to the same, as shown in Fig. 10.

I claim as my invention—

The combination with the arbor and spring-barrel having a hub through which the arbor passes, of a ring around and supported by the hub, a pin for receiving the end of the spring, a disk connected with the arbor and 95 having an opening therein and a pin on the ring entering such opening, the opening in the disk being of larger diameter than the pin so that the pin engages with the disk and serves to connect the arbor and disk with the 100 ring and spring, substantially as specified.

In testimony that I claim the foregoing as my invention I have signed my name in presence of two subscribing witnesses.

CHARLES MORLET.
